UNITED STATES PATENT OFFICE.

CHARLES W. SMITH, OF NORWALK, OHIO.

DESIGN FOR A CURTAIN-POLE BRACKET.

SPECIFICATION forming part of Design No. 21,930, dated October 25, 1892.

Application filed September 26, 1892. Serial No. 446,963. Term of patent 7 years.

To all whom it may concern:

Be it known that I, CHARLES W. SMITH, a citizen of the United States, residing at Norwalk, in the county of Huron and State of Ohio, **5** have invented certain new and useful Improvements in a Design for Curtain-Pole Brackets; and I do declare the following to be a full, clear, and exact description of the invention, such as will enable others skilled in **10** the art to which it appertains to make and use the same, reference being had to the accompanying drawings, and to the letters of reference marked thereon, which form a part of this specification.

15 Figure 1 is a side elevation of a curtain-pole bracket embodying my design. Fig. 2 is a transverse section on the line xx of Fig. 1.

My design has reference to brackets for curtain-poles.

20 My bracket consists, essentially, in a part to be engaged by the curtain-pole and a stem or shank. Said pole-engaging part comprises the two disk-like or circular pieces A and A, separated a distance from each other equal, **25** substantially, to the diameter of the pole to be supported, and the connecting-neck a . The latter is circular in cross-section, and its sides

are concave and formed substantially on the arc of a circle. The outer side of each piece A is concave and is the section of a sphere. **30** The pole-engaging part is carried by the stem or shank B, which is united to one of the pieces A at its center. Said stem comprises a reduced cylindrical portion b and an enlarged cylindrical portion b' , which are united **35** by the ornamental annular portion b^2 , whose sides are defined by a compound curve. The enlarged portion constitutes the base-piece of the bracket. Said enlarged portion is formed with an ornamenting circumferential **40** groove b^3 , and at the junction of the stem and the inner piece A of the pole-engaging part is turned a bead a' . Attached to the outer circular piece A, on its concave side, at its center, is an ornamental projection a^2 . **45**

What I claim is—

The design for a curtain-pole bracket, substantially as shown and described.

In testimony whereof I affix my signature in presence of two witnesses.

CHARLES W. SMITH.
